Application filed July 18, 1885. Serial No. 171,987. Term of patent 7 years.

To all whom it may concern:

Be it known that I, FREDERICK MANKEY, of Williamsport, Lycoming county, Pennsylvania, have invented and produced a new and 5 original Design for Surface Ornamentation of Walls, &c., of which the following is a specification, reference being had to the accompanying photograph, forming part hereof.

My design consists in a series of elevations, A, arranged in regular rows, side by side, trans- 15 versely and longitudinally upon the surface. Each elevation consists of a rectangular base portion surmounted by a pyramid. The said elevations are separated by channels B, formed transversely the surface, and by chan- 20 nels C longitudinally the surface, said chan-
